COMB

Earl S. Tupper, Harvard, Mass.

Original application August 6, 1940, Serial No. 351,611. Divided and this application December 1, 1941, Serial No. 421,098

8 Claims. (Cl. 132—11)

This invention relates in general to combs, and more particularly to combs for hairdressing purposes.

Objects of the invention include the provision of a rat-tail handle comb having means by which liquids may be scooped up and applied to the hair; the provision of means by which the handle of the comb is utilized to take up and retain such liquids as water, hair-lotion, wave-set, tonic, coloring, or other fluid materials; the provision of a comb handle which will form curls when the hair is wrapped therearound; the provision of means comprising grooves in the rat-tail handle of the comb for wetting the formed curl on the inside of the curl, such means also being used to guide hair pins into curls formed on the handle; and the provision of a light weight comb having attractive means for a more rapid, accurate, and even method of forming curls.

Other objects and advantages of the invention will appear hereinafter.

Reference is to be had to the accompanying drawing, in which

Fig. 1 is a front elevation of a comb embodying one form of the invention;

Fig. 2 is a section on line 2—2 of Fig. 1;

Fig. 3 is a front elevation of another form of the invention, with parts broken away;

Fig. 4 is a section on line 4—4 of Fig. 3;

Fig. 5 is a front elevation of a further form of the invention; and

Fig. 6 is a sectional view through the teeth of a still further modification.

Figs. 1 and 2 disclose a comb having a back 10 to which the roots of the teeth of an ordinary comb are connected. In the present instance, teeth 14 may correspond in depth, i. e. distance from side to side of the comb, to the teeth of the conventional comb, as will be apparent from Fig. 2. These teeth 14 may occur every third tooth, the two intervening teeth 16 being much less in depth than teeth 14, so that in effect teeth 14 rise up or extend out to a greater distance than teeth 16. This arrangement may be made with alternate deep teeth, or with every fourth, fifth, etc. tooth a deep tooth, depending on the appearance desired, or other conditions. Also, the deep teeth 14 may be raised above normal teeth, or the teeth of less depth may be sunken below the normal teeth, the latter condition being that disclosed in Figs. 1 and 2. Also, of course, the deep teeth 14 may appear on both sides of the comb.

The comb back 10 may be cut or molded along curved lines to form rear walls 20, and as shown, 55

three-sided enclosures having bottoms 22 are thus provided, such bottoms being in the same general plane as the front faces of teeth 16.

The effect of the above-described structure is to present a series of thin transverse dams, composed of teeth 14 and a rear wall 20, between each dam, to provide an enclosure or shelf for the scooping up and retention of liquids, without, however, affecting the use of the comb per se. 10 Hence, a comb embodying the present invention may be dipped into a bottle of wave-set, coloring, tonic, etc. and relatively large amounts of such liquid will be retained between the dams, thus avoiding the application of the liquid by 15 separate means. The surface tension of the liquid will insure against its falling through the spaces between the teeth and therefore teeth 16, together with surfaces 22 will form the bottom of a large shelf area for liquid retention. This 20 structure provides for picking up a many times greater volume of liquid than combs in the prior art.

Also, the dams will prevent the liquid from flowing down to one end of the comb, as usually 25 happens, and keep the liquid evenly distributed over the entire comb area which has been dipped in a bottle or held under a water-tap. This results in avoidance of spilling the liquid on the clothes when the comb is not in horizontal position.

A further use of the present comb resides in its capability to scrape excess liquids and oils 30 from the hair, since it is clear that upon running the comb through the hair, such excesses will be deposited on the shelves formed by the bottoms 22.

Figs. 3 and 4 show a modification of the invention wherein all the teeth 24 and 26 are of the same depth, but the latter have been reduced at 35 the lower back area 28, so that smaller enclosures are formed, these enclosures being limited by the back area 28, teeth 24 and back 30. These 40 enclosures perform the same functions as the shelves disclosed in Fig. 1, but of course are smaller.

Fig. 5 shows the preferred embodiment of the invention, wherein the teeth and back may be 45 similar to either that of Fig. 1 or of Fig. 3, but a rat-tail handle 32 is applied. This rat-tail has 50 a groove 34 longitudinally thereof, and this groove not only adds to the appearance of the handle and reduces the weight and expense of the comb, but forms a guide by which a bobby pin may be slid up into a curl, which has been previously rolled on the handle. This is a very

convenient means by which the curl may have a pin applied to hold it without mussing or bunching up the curl. There may be a groove 34 on each side of the rat-tail.

Fig. 6 presents a still further modification in which the teeth 40 are staggered, as seen in cross-section, so that liquid retaining enclosures 42 are formed on both sides of the comb.

It is to be understood that the grooved rat-tail 32 may be used with any of the tooth forms, and that any tooth form may appear on one or both sides of the comb, and it is further particularly pointed out that grooves 34 in handle 32 are used as liquid retaining receptacles for moistening the interior of curls formed thereon so that the curls will be wet inside and thus will be enabled to hold their shapes better. Also, the construction illustrated in Fig. 5 shows that the groove is not open ended, but is stopped at its ends by the material of the handle, and the liquid cannot escape except by flowing over the raised ridge which extends completely around the groove.

This application is a division of my application Serial Number 351,611, filed August 6, 1940, now 25 Patent Number 2,264,346, dated December 2, 1941.

Having thus described my invention and the advantages thereof, I do not wish to be limited to the details herein disclosed, otherwise than as 30 set forth in the claims, but what I claim is:

1. A comb having a rat-tail handle, a longitudinal groove in said handle, and a closed liquid tight bottom for said groove, said bottom providing a hair pin guide.

2. A comb having a rat-tail handle, a longitudinal groove in said handle, said groove having a closed, imperforate bottom and continuous side walls forming a liquid holding pin guide for curls on said handle and a positive hair pin guide.

3. A comb having rat-tail handle, a longitudinal groove in said handle, said groove having a

closed bottom, continuous side walls, and a closed end, said groove forming a liquid-retaining pocket in said handle and being capable of use as a guide for hair pins, whereby said hair pins cannot project through the handle from side to side thereof.

4. A comb of the class described having a long narrow handle at one end thereof, said handle being provided with a longitudinal groove in at least one side thereof, said groove having an imperforate bottom and continuous side-walls to form a liquid holding recess and a positive hair pin guide.

5. A comb as recited in claim 4 wherein said groove is closed at at least one end to form a liquid retaining receptacle.

6. A comb having a tapered rat-tail handle, a longitudinal tapered groove in said handle, said groove having an imperforate bottom and continuous side walls so that said groove forms a liquid retaining pocket in the handle and a positive hair pin guide.

7. A comb having two series of teeth, the teeth of one series extending at least in part laterally of the comb beyond the teeth of the other series, said teeth of said one series being greater in depth than the teeth of the other series, and a rat-tail handle for said comb, and a groove in a side of said handle, said groove and said teeth forming separate liquid retaining means in a side of the comb.

8. A comb having a rat-tail handle, a longitudinal groove in said handle at opposite sides thereof, said grooves having imperforate sides and bottoms and providing liquid holding pockets so that liquid in said pockets will be applied to hair curled on said handle, and said pockets also providing hair pin guides, so that the pins cannot extend through the handle by reason of the 40 imperforate bottoms.

EARL S. TUPPER.
